(57) **CLAIM**

A new original design for projector, substantially as shown and described.

DESCRIPTION

FIG. 1 is a front, top, right-side perspective view of a design of a portion of the projector;

FIG. 2 is a top elevation view thereof, wherein the bottom and rear features are identical, and disclaimed, with the exception of the lens housing; and,

FIG. 3 is a left-side elevation view thereof.

Wherein the broken lines form no part of the claimed design.

1 Claim, 2 Drawing Sheets

FIG. 1

FIG. 2

FIG. 3
